UNITED STATES PATENT OFFICE.

ROBERT HALLEY, OF CHICAGO, ILLINOIS, ASSIGNOR OF ONE-FOURTH TO THE PLANO MANUFACTURING COMPANY, OF CHICAGO, ILLINOIS, A CORPORATION OF ILLINOIS.

ADJUSTABLE FURNACE.

SPECIFICATION forming part of Letters Patent No. 707,104, dated August 19, 1902.

Application filed August 2, 1901. Serial No. 70,589. (No model.)

To all whom it may concern:

Be it known that I, ROBERT HALLEY, a resident of Chicago, in the county of Cook and State of Illinois, have invented certain new and useful Improvements in Adjustable Furnaces, of which the following is a specification.

My invention relates to furnaces used in the blacksmith-shops of manufacturing establishments, and is designed to produce a furnace in which bars of iron can be heated on a single furnace at two different points on their length, and it is designed to make the furnace adjustable, so that the distance between these points can be varied, as may be necessary in producing different sizes of the same piece or different pieces.

My invention is also concerned with a furnace which is adjustable to vary the effective width thereof, so that greater or less portions of rods may be heated, as may be desired.

Referring to the accompanying sheets of drawings, in which the same reference characters are used to designate identical parts in all the figures, Figure 1 is a side elevation of the furnace. Fig. 2 is a plan view of a portion thereof. Fig. 3 is an end elevation of the lower ends of the supporting-legs of the movable member of the furnace. Fig. 4 is a detail to be explained; and Fig. 5 is a plan view similar to Fig. 2, but with the removable wall in position.

The complete furnace consists of a stationary member 5 and a movable member 6. The stationary member 5 is provided with the legs 7, by which it is supported, which legs rest wherever the furnace may be placed. The movable member is provided with the legs 8, which have the rollers 9 journaled in their lower ends and resting upon the metallic strips or rails 10, which may be laid down wherever needed in proper relation to the stationary member. As shown in Fig. 3, I preferably provide one of the rollers 9 with a groove 11 in its periphery, which cooperates with a rib 12 on the upper side of its rail 10, so that the member will be guided thereby. The legs of each of the members are secured to and support the base-plate 13 of the furnace, and the

ends 14 rest upon the edges of the base-plate 50 and may be secured thereto, if desired. The sides 15 are provided at each end with the segmental flanges 16, which are pivoted to the ends 14 at their lower edges, as by the bolts 17.

Concentric with the bolts 17 are the segmental slots 18, through which pass the bolts 19, which take into the end plates 14. By this mechanism it will be seen that within certain limits the width of the top of the furnace members may be varied, so as to heat 60 different lengths of rods on the same furnace. The interior walls and the bottom of the furnace are lined with the fire-bricks 20 in the customary manner after the sides 15 have been adjusted as may be desired for the work 65 in hand. The movable member 6 is provided with a burner 21, which may be of any desired construction and directs the flame into the furnace from one end thereof. The stationary member 5 is provided on one end, 70 near one side, with the burner 22 and on the other end, near the other side, with the burner 23. If it is desired to heat two portions of a rod quite close to each other, the solid partition-wall 24, of fire-brick, may be 75 built across the middle of the furnace, as indicated by the dotted lines in Fig. 2. If it is desired to heat a bar through a portion of its length equal to the width of the stationary member 5, the partition 24 is omitted, and 80 with the arrangement of the burners 22 and 23 as shown the flame, as indicated by the lines in Fig. 2, will circle around the edges of the furnace, producing a rotary movement that is very effective in heating the entire 85 width and length of the furnace. One of the members, preferably the stationary member, is provided on its under side with the bearing 25 for the shaft 26, which has the handle 27 in its outer end, by which it may be rotated, 90 and the collar 28 next to the bearing, by which it is held from longitudinal movement. The portion of the shaft 26 which extends beyond the stationary member 5 is screw-threaded, as shown, and passes through the screw-threaded aperture 29 in the bearing 30, (see Fig. 4,) 95 secured to the under side of the movable furnace, so that by turning the handle 27 the

movable member may be adjusted in any desired position relative to the stationary member. By this arrangement it will be seen that I am enabled to quickly adjust the furnaces 5 without dismantling them in any desired relation to each other, so as to heat two portions of a bar at any desired distance between said portions.

The burners 22 and 23 are provided with 10 the stationary pipes 31 and 32, through which a blast of air is driven from any desired source to furnish the necessary supply of oxygen for burning the oil, which is conveyed to the burners in the pipes 33, the pipe 33 for the burner 15 23 not being shown. To provide the air-supply for the burner 21, I extend from the pipe 31 the horizontal branch 34, into which is telescoped by a substantially air-tight joint the horizontal portion of an L-shaped air-pipe 35, 20 which supplies air to the burner 21. These air-pipes may be provided with such valves as are deemed necessary for controlling the passage of the air through them; but I have not deemed it necessary to illustrate these 25 valves in detail, as they form no part of my invention.

To furnish oil to the movable furnace from the pipe 33, I place in the horizontal pipe 36, which connects the top of the pipe 33 with 30 the burner 23, a T-shaped sleeve 37, which is screwed onto the ends of the sections of the pipe 36, so as to permit the oil to pass from the pipe 36 into the T-shaped sleeve 37 and thence into the pipe 38, which is screwed into 35 the sleeve 37 in the manner clearly shown. A valve 39, for controlling the admission of oil to the burner 22, is placed in the pipe 36 between the sleeve 37 and the burner. A horizontal pipe 40, having the valve 41 therein to 40 control the admission of the oil to the burner 21, has screwed on its outer end the elbow 42, which has one end of the pipe 43 secured therein. The lower end of the pipe 38 has secured thereon the elbow 44, and the lower 45 end of the pipe 43 has secured thereon a similar elbow 45, the two elbows 44 and 45 being connected by the short pipe 46, which is screwed into the said elbows, so that as the members 5 and 6 are moved relative to each 50 other the sleeve 37 turning upon the sections of the pipe 36, the elbow 42 turning upon the end of the pipe 40, and the elbows 44 and 45 turning upon the pipe 46 will permit of the angular variation between the pipes 38 and 55 43 that is necessitated by the different positions of the two members. With the telescoping connections between the air-pipes and the swinging connections between the oil-pipes it will be seen that the air and oil supply for the 60 movable member 6 of the furnace will be maintained whatever distance may separate the two members.

It will be seen that by my invention I provide a furnace that is adjustable not only to 65 vary the length of the heating-surfaces, but which is adjustable to furnish two heating-surfaces of different distances from each other,

and with this furnace I am enabled to heat rods and bars in almost any way that may be necessary in the manufacture of machinery. 70

While I have shown my invention as embodied in the form which I at present consider best adapted to carry out its purposes, it will be understood that it is capable of modification, and I do not desire to be limited in the 75 interpretation of the following claims, except as may be necessitated by the state of the prior art.

What I claim as new, and desire to cover by Letters Patent of the United States, is— 80

1. In a furnace, the combination with the stationary furnace member, of the movable furnace member, said members having the surfaces upon which the articles to be heated are placed in substantially the same plane, 85 adjustable oil and air pipe connections between said members, and means for moving said movable member in the plane of the said surfaces so that the articles can be heated at points different distances apart, substantially 90 as described.

2. In a furnace, the combination with the furnace member having a burner at one end thereof and the oil-pipe and air-pipe leading to the said burner, of the movable furnace member having a burner at one end thereof, the heating-surfaces of said members upon which the articles to be heated are placed being in substantially the same plane, the 95 adjustable oil and air pipe connections between the air and oil pipes of the burner on the stationary member and the burner on the adjustable member, and means for moving said movable member in the plane of the said surfaces so that the articles can be heated at 100 points different distances apart; substantially 105 as described.

3. In a furnace, the combination with the stationary furnace member having a burner at one end thereof, and the air-pipe and oil-pipes leading to said burner, of the movable furnace member having a burner at one end thereof, the telescoping air-pipe connections between the burner on the movable member and the air-pipe for the stationary member, 110 and the pipes 38 and 43 pivotally connected at both ends thereof between the oil-pipe on the stationary member and the burner on the movable member, all coöperating substantially as and for the purpose described. 115

4. In a furnace, the combination with the stationary furnace member, of the movable furnace member, burners for each of said members adjustable oil and air pipe connections between said members, and means for adjusting the movable member relative to the stationary member consisting of the screw-threaded rod secured to rotate in one of said members and coöperating with the screw-threaded aperture in the other of said members. 125

5. In a furnace, the combination with the stationary furnace member, of the movable furnace member mounted on rollers, adjust-

able oil and air pipe connections between said members, and means for adjusting the movable member consisting of the screw-threaded rod secured to rotate in one of said members and coöoperating with the screw-threaded aperture in the other of said members.

5. In a furnace, the combination with the base-plate, of the stationary ends, and sides pivotally secured at their lower ends to the base-plate to increase or diminish the breadth of the furnace-top.

6. In a furnace, the combination with the base-plate, of the stationary ends, the sides provided with the segmental flanges overlapping the ends and pivoted thereto at their lower ends, and means for securing the sides in any desired position of adjustment.

7. In a furnace, the combination with the base-plate, of the stationary ends, the sides provided with the segmental flanges overlapping the ends and pivoted thereto at their lower ends, and means for securing the sides in any desired position of adjustment.

8. In a furnace, the combination with the base-plate, of the stationary ends, the sides

20 provided with the segmental flanges overlapping the ends and pivoted thereto at their lower ends, and means for securing the sides in any desired position of adjustment.

ping the ends and pivoted thereto at their lower ends, and means for securing the sides in any desired position of adjustment, consisting of the segmental slots in said flanges concentric with the pivotal points thereof 25 and the bolts 19 passing through said slots into the ends substantially as and for the purpose described.

9. A furnace of the class described, having a rectangular fire-box with an oil-burner located so as to direct the flame inwardly from one end near one side, and another similar burner located so as to direct the flame inwardly from the other end near the other side, and adapted to have a temporary wall 30 extending between the centers of the ends.
